US00D877766S

(12) **United States Design Patent** (10) Patent No.: **US D877,766 S**
Li et al. (45) Date of Patent: **** Mar. 10, 2020**

(54) **INSTRUMENT DISPLAY SCREEN OR PORTION THEREOF WITH GRAPHICAL USER INTERFACE FOR PREPARATION OF BIO-BLOCK**

(71) Applicant: **REVOKEK CO., LTD**, Sichuan (CN)

(72) Inventors: **Lin Li**, Sichuan (CN); **Xiaolin Hu**, Sichuan (CN)

(73) Assignee: **REVOKEK CO., LTD**, Sichuan (CN)

(**) Term: **15 Years**

(21) Appl. No.: **29/654,781**

(22) Filed: **Jun. 27, 2018**

(51) LOC (12) Cl. **14-04**

(52) U.S. Cl.

USPC **D14/486**

(58) **Field of Classification Search**

USPC D14/485-495

CPC G06F 3/048; G06F 3/0481; G06F 19/3406

(57) **CLAIM**

The ornamental design for instrument display screen or portion thereof with graphical user interface for preparation of bio-block, as shown and described.

DESCRIPTION

The FIGURE is a front view of instrument display screen or portion thereof with graphical user interface for preparation of bio-block, showing our new design.

The broken lines showing a display screen and elements of the graphical user interface illustrate portions of the article, and form no part of the claimed design.

1 Claim, 1 Drawing Sheet
